UNITED STATES PATENT OFFICE.

JESSE A. B. SMITH, OF STAMFORD, CONNECTICUT; ASSIGNOR TO UNDERWOOD TYPE-WRITER COMPANY, OF NEW YORK, N. Y., A CORPORATION OF DELAWARE.

TYPEWRITING MACHINE.

Application filed May 18, 1920. Serial No. 382,229.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriting machines, and is illustrated in connection with an Underwood standard typewriting machine. In attempting to use typewriting machines for making out small bills, it is found that the manual operations of inserting and line-spacing the bill-head usually involve so many motions that it is more economical to make out such bills with pen and ink. Devices have been made for typing such bills, but they have been either limited 10 to bills in which all the typing was to be done on a single line, or on a very few lines, or were limited to bills of a single size, with the result that the machine used for one size of bills could not well be used for another 15 size.

An object of the invention is to produce an improved device for use in typing these short bills and also useful when a large number of sheets, such as ledger-sheets, are to be reinserted in the machine periodically (for example, daily, monthly or quarterly) for the 20 typing of new items thereon, thus adapting the machine, by means of a single device, for a large variety of work which commonly, 25 heretofore, has required separate devices, and a further object, in this connection, is a widening of the range or capacities of the machine as to the classes of work handled, together with increased convenience and 30 effectiveness.

According to the present invention, the typewriting machine may include devices for holding a work-sheet, upon which one, two, or three lines are to be typed in its bottom margin, and may be adapted to line-space the bill or work-sheet independently of the line-spacing of the platen, and these holding devices may be so constructed that bills of any one of a number of sizes may be 45 insertable therein with substantially equal facility, and may be automatically gaged at their insertion. The machine may also include the usual line-spacing devices which co-operate with the platen, thus providing 50

means for line-spacing a ledger-sheet independently of the line-spacing of any of the various sizes of bills that may be held by the first described devices.

The devices for line-spacing a bill may include a finger-piece which is adapted to be pushed to the left when the typewriter carriage is to be returned to the right by the usual platen-line-spacing device, thus making the line-spacing operation involve a natural combination of movements. The finger-piece may be connected to the bill-holding gage-plate or device by a cam or cams, to positively move it in each direction.

Also, according to the present invention, in cases in which, as above noted, a large 70 number of sheets are to be re-inserted in the machine periodically, for the insertion of new items for each period, the sheets may be automatically gaged at new master line-space positions corresponding to the different periods, and also may be independently line-spaced at each of said positions so that each item may comprise more than one line.

To this end, a leading-edge gage or an aligning plate provided with a leading-edge 80 gage and erected at the front of the platen above the printing line may be settable by mechanically-determined master line-space stages or intervals to occupy a series of different master line-space positions corresponding to the respective minor business 85 periods which make up or are comprised in a major business period. The minor business periods may be the days of the month, the month then being the major business period; or the minor business periods may be months, and the major business periods may then be a year; or such major and minor business periods may be arranged in the manner which may be most convenient in any particular instance.

According to the present invention as disclosed herein, an aligning plate provided with a leading-edge gage may be line-spaced upon a pair of mounts which are settable by master line-space stages or intervals upon a pair of plate-supporting uprights bars at the delivery side of the platen.

Other features and advantages will hereinafter appear.

In the accompanying drawings,

Figure 1 is a fragmentary front view of an Underwood typewriting machine, show-

ing the present invention applied thereto, when the bill-head is being removed after being typed.

Figure 2 is a sectional plan view of the same.

Figure 3 is a front view similar to Figure 1, but showing the work-sheet inserted, and before it has been typed.

Figure 4 is a sectional side view of the parts seen in Figure 1.

Figure 5 is a rear view of the work-sheet-holding plate and its line-spacing device, in the position shown in Figure 3.

Figure 6 is a view similar to Figure 5, but showing a modification.

In the usual Underwood standard typewriting machine, there may be passed around the platen 10, journaled in the ends 11 of a shift-frame, a ledger-sheet 12, having in front of it a carbon-sheet 13. These lie upon the rear paper-table 14 and are held against the platen by rear feed-rolls 15 and front feed-rolls 16, and are carried up past the printing line, shown diagrammatically by the type-head 17. The type-head 17 is on the end of a type-bar 18 pivoted on the segment 19 and striking between the arms of a type-guide 20 on either side of which lies a wing-scale 21. The shift-frame 11 forms part of a carriage 22 which travels along upon the frame 23 in the usual manner. According to the present invention, the carriage may be brought to the right-hand limit of its travel as shown at Figure 1, so that a work-sheet or bill-head 24 may be inserted from the side behind the adjacent wing-scale 21 and laid upon a gage-plate 25. The bill 24 is adapted to be gaged against the turned-over upper edge 26 of the gage plate, and its turned-up left-hand edge 27. When the bill-head has been thus gaged, it is held upon the gage-plate 25 by turned-over spring-fingers 28 which hold it in its gaged position and are adapted to move it in the line-spacing operation when a line-space finger-piece 29 is actuated. For the purpose of line-spacing the ledger-sheet 12, the usual Underwood line-space mechanism may be used including the line-space wheel 30, and the line-space pawl 31. Since, however, the bill-head 24 is not held by the feed-rolls 15 or 16, but lies in front of them, having its lower end behind the wing-scale 21, as shown in Figure 4, the line-spacing of the ledger-sheet is without effect upon the bill-head 24.

Ordinarily, the first line upon the bill-head 24 is typed without actuating the line-space finger-piece 29. When, however, the carriage is returned to write a second line upon the bill-head 24, the typist usually returns the carriage by the line-space handle, not shown, actuating the line-space wheel 30; and, in accordance with the present invention, may at the same time press the fin-

ger-piece 29 to the left, thus line-spacing the bill 24 at the same time that the ledger-sheet 12 is line-spaced. The line-space connections between the finger-piece 29 and the gage-plate 25 include a cam-plate 32, of which the finger-piece 29 forms an extension, said plate 32 being guided by studs in the form of shouldered screws 33, which are threaded into lugs or mounts 34 and locked in place by lock-nuts 35. The cam-plate 32 slides upon the screws 33 because it is provided with horizontal slots 36 for this purpose. To enable the finger-piece 29 to cam up on the gage-plate 25, the cam-plate is also provided with cam-slots 37, in which run posts or pins 38, which project from the aligning plate or gage-plate 25, the relationship being such, in Figures 1 to 5, that pushing upon the finger-piece 29 positively lifts the gage-plate 25 from its Figure 1 to its Figure 3 position. Later drawing the finger-piece 29 outwardly positively returns the gage-plate 25 to its first position.

In order to detain the finger-piece 29 in either of its positions, there is provided a flat detent-spring 39 having a projection adapted to seat itself in openings 40 or 41 of the cam-plate 32. To permit the gage-plate 25 to be adjusted to suit various lengths of bill-heads, or for repositioning ledger-sheets upon which daily, monthly or quarterly entries, or the like, are to be made, the lugs or mounts 34, above described, may be supported upon upright L-bars 42, which slope rearwardly and are provided with spaced openings 43, into which thumbscrews 44, upon upper lugs 45 extending from the lugs or mounts 34, are adapted to be threaded. The L-bars 42 are supported upon cross-rods 46 and 47 which extend across the shift-frame 11, being made fast on upright brackets or plates 48, held by screws 49 to the ends of the shift-frame 11.

To give rigidity to the structure, the rods 46 and 47 may be held fast in one of the plates 48 by riveting, and may be connected to the other plate 48 by nuts 50, which are threaded onto the extensions 51 of their respective rods, thus allowing the nuts 50 to be screwed up tight after the brackets 48 have been placed in position and their screws 49 securely tightened.

It has been found most satisfactory usually to have the openings 43 at double line-space distances from each other, thus giving greater rigidity to the L-bars 42 and yet enabling a sufficiently wide variety of bill-heads 24 to be used, and also thereby providing the usually desired spacing between the successive items of a reinserted and repositioned ledger-sheet which may lie upon the aligning plate 25 at the back of the bill 24, or other bill, instead of passing below and to the rear of the aligning plate 25, as does the ledger-sheet 12 shown in the drawings. For

convenience, the numeral associated with the holes 43 may be considered as indicating the positions to be assumed by the mounts 34 to position the gage-plate 25 for different 5 monthly entries on ledger-sheets. The L-bars 42 may be adjustably held by set-screws 53, threaded into collars 54, said collars embracing the rods 46 and 47, respectively.

In order to guide the gage-plate 25 vertically, the screws or studs 33 may have their heads 55 lying above it and running in countersunk portions 56, provided with transversely slotted openings 57. The openings 57 form straight guides which engage the 15 screws 33.

The pair of upright bars 42 having therein the holes 43 spaced at double-line distances apart for receiving the screws 44 of the mounts 34 provide means whereby the 20 aligning plate 25 and leading-edge gage 26 are settable by mechanically-determined master line-space stages or intervals to occupy line-space positions relatively to the printing line on the platen corresponding to 25 the respective hereinbefore-mentioned minor business periods to provide for the typing of an entry of one or more lines at each master line-space position for each of the series of 30 separately inserted work-sheets, and in the drawings these screw-receiving holes 43 are shown as provided with indices and as numbered to represent the respective business days of a month.

In using the device in this way the work-sheet, which may be a ledger-sheet, may be inserted in the machine from the rear around beneath the platen 10, and gaged at its leading edge against the leading-edge gage 26 and held in place on the aligning plate 25 by means of the sheet-holding clips 28 in any one of the proper line-space positions indicated by the numbered indices for the corresponding day of a month. The first line of an entry for this date may now be 45 written. If another line is required to complete the item or entry, finger-piece 29 may be actuated, as hereinbefore described, to line-space the aligning plate 25 and the work-sheet held thereon to an intermediate position between the above-described master line-spaced positions. However, it will of course be necessary for line-spacing the aligning plate 25 first either to line-space the platen 10 or to cast off platen feed-rolls 15 and 16. 50 After corresponding entries have thus been made upon all of the series of sheets for one date, the mounts 34 may be set up at double line-space intervals on the upright bars 42 to provide for making similar entries on the 55 same sheets on the next following date. For each business period or day the finger-piece 29 may be actuated for typing the second line of an item to an intermediate position between the master line-space or double line-space positions. In using the device

above mentioned in this way the usual outer bill-sheet or invoice will be inserted around the platen, in order to provide for conveniently adjusting it relatively to the ledger-sheet held upon the platen, and held on the 70 aligning plate 25 so as to be line-spaced thereby.

The device shown in Figures 1 to 5 usually provides only for a single line-spacing operation, or two line-space positions of the 75 aligning plate 25 and leading-edge gage 26, thus providing for the writing of only two lines upon a bill-head 24, or other work sheet. It is found that, in the usual Underwood standard typewriting machine, 80 fully three lines of a work-sheet can be utilized for typing when inserted from the front in the manner described. To enable the three lines to be typed, the modified form of device shown in Figure 6 may be 85 utilized, in which the pins 38 run in the special cam-slots 58, provided with a central dwell 59, at which the finger-piece 29 may hold the pins 38 to hold the gage-plate 25, and enable the typing of a middle line 90 upon the bill-head. Each cam-slot 58 also comprises a dwell 60 at each end, corresponding to a short dwell at each end of the cam-slots 37. The device shown in Figure 95 6 has a spring-detent 39 like the device shown in Figure 5, but is provided with three depressions 61 instead of the two depressions shown in Figure 5, owing to the difference in the number of lines to be typed. The detent-spring 39 in each case may be 100 held by screws 62 threaded into one of the lugs 34. Since the bill-heads are somewhat stiff, the fingers 28 may be easily flexed and the bill-heads easily slipped under their turned-up ends.

Variations may be resorted to within the scope of the invention, and portions of the improvements may be used without others.

Having thus described my invention, I claim:

1. In a typewriting machine, the combination with a carriage having a carriage-return finger-piece thereon and a platen mounted therein, of a gage-plate upon the carriage, a clip upon the plate to hold a work-sheet thereon, and a finger-piece to line-space the plate and sheet thereon, the line-spacing finger-piece being located adjacent the carriage-return finger-piece, so that they may be grasped at the same time and the line-spacing finger-piece pressed towards the carriage-return finger-piece to line-space the gage-plate as the carriage is being returned to the right by the carriage-return finger-piece.

2. In a typewriting machine, the combination with a platen-frame and a platen journaled therein, of a pair of uprights in said frame, a gage-plate, an adjustable support for said plate on said uprights, means

105

110

115

120

125

130

for holding a work-sheet on the gage-plate, and a line-spacing device for moving said plate with reference to said support to line-space the work-sheet held thereupon.

- 5 3. In a typewriting machine, the combination with a platen-frame and a platen journaled therein, of uprights in said frame, a gage-plate, an adjustable support for said plate on said uprights, a cam-plate slidable
10 on said support, and a finger-piece adapted to shift the cam-plate to line-space a work-sheet held on the gage-plate.

4. In a typewriting machine, the combination with a carriage and a platen therein, of a gage-plate adjustable to different heights upon the carriage, a clip upon said plate, a line-spacing finger-piece, a pin-and-cam connection between the finger-piece and the gage-plate, and a dwell in the cam at each line-space position of the finger-piece to hold the plate in position.

5. In a typewriting machine, the combination with a platen-frame and a platen journaled therein, of uprights in said frame, 25 a gage-plate, an adjustable support for said plate on said uprights, a pair of pin-and-cam connections on the support to move the gage-plate, and a finger-piece for operating said connections to line-space a work-sheet, 30 held on the gage-plate.

6. In a typewriting machine, the combination with a platen-frame and a platen journaled therein, of uprights in said frame, a gage-plate, an adjustable support for said plate on said uprights, a cam-plate slidable on said support, a finger-piece adapted to shift the cam-plate to line-space a worksheet held on the gage-plate, and screws in said support upon which the gage-plate slides and adapted to guide the cam-plate.

40 slides and adapted to grade No. one plate.

7. In a typewriting machine, the combination with a platen-frame and a platen journaled therein, of uprights in said frame, a gage-plate, an adjustable support for said plate on said uprights, means for holding a work-sheet on the gage-plate, a line-spacing device for moving said plate to line-space the work-sheet held thereupon, and a thumb-screw for each upright adapted to enter 45 aligned openings to hold the support in position.

8. In a typewriting machine, the combination with a platen-frame and a platen journaled therein, of uprights in said frame, a gage-plate having one side gage and a leading-edge gage, so that a work-sheet can be inserted from the side, clips to support the sheet adapted to receive it when pushed side-wise and upwardly, a support for said gage-plate adjustable on said uprights, and a finger-piece for moving the plate relatively to said support to line-space the work-sheet held thereon.

9. In a front-strike typewriting machine, the combination with a segment and a trav-

eling carriage, of uprights on the carriage, a mount upon each upright, a thumb-screw for each mount so that the screws enter aligned openings in the uprights, a stud on each mount, a gage-plate comprising openings to fit the studs and guide it when sliding, a cam-plate comprising openings sliding on the studs, and a pair of cams on said cam-plate adapted to positively move the gage-plate up and down to line-space a work-sheet thereon behind the platen. 70 75

10. In a typewriting machine, the combination with a platen-frame and a platen journaled therein, of uprights in said frame, a gage-plate, an adjustable support for said plate on said uprights, means for holding a work-sheet on the gage-plate, a line-spacing device for moving said plate relatively to said support to line-space the work-sheet held thereupon, and a separate line-spacing device for the platen. 85

11. In a typewriting machine, the combination with a platen-frame and a platen journaled therein, of uprights in said frame, a gage-plate, an adjustable support for said plate on said uprights, a cam-plate slidable on said support, a finger-piece adapted to shift the cam-plate to line-space a worksheet held on the gage-plate, and a separate line-spacing device for the platen. 90 95

12. In a front-strike typewriting machine, the combination with a cylindrical platen, of a leading-edge gage at the delivery side of the platen, a mount for said gage, adjusting means for detaining said mount at a plurality of positions at different distances from the printing line, each position of the mount corresponding to the depth of the heading above the first writing line of each of a plurality of work-sheets to be inserted in succession and gaged by said leading-edge gage, means for detaining against said gage a work-sheet gaged thereby, and line-spacing means for advancing said leading-edge gage from its normal position on said mount to advance the work-sheet detained thereagainst to another line-space position without change in the position of said mount. 100 105 110

13. In a front-strike typewriting machine, the combination with a cylindrical platen, of a gaging device-carrying mount, means for locating and detaining said mount at any one of a series of mechanically-determined equally-spaced positions to vary the distance of said mount from the printing line, a gaging device on said mount, and means for locating and detaining said gaging device on said mount at any one of a series of mechanically-determined equally-spaced positions, so that the position of the gaging device may be varied without change in the position of said mount. 115 120 125

14. In a front-strike typewriting machine, the combination with a platen, of a pair of gage-supporting upright bars at the delivery end. 130

ery side of the platen, a gage-carrying mount upon each of the bars and movable thereon relatively to the printing line, means to detain said mounts in adjusted position on 5 said bars, a leading-edge gage on said mounts, and means to locate and detain said gage at any one of a series of different mechanically-determined spaced positions to vary the position of said gage relatively to 10 the printing line.

15. In a front-strike typewriting machine, the combination with a platen, of an aligning plate erected at the front of the platen and provided with a leading-edge gage, a 15 mount on which said plate is shiftable, a support on which said mount is shiftable, means for locating and detaining said plate at mechanically-determined positions at different distances from the printing line, and 20 means for line-spacing said aligning plate.

25. In a front-strike typewriting machine, the combination with a platen, of an upright plate-support at the introductory side of the platen, an aligning plate movable up and down along said support, means for detaining said aligning plate in adjusted positions corresponding to different successive business periods, means for holding a work-sheet on said plate, and a line-spacing device 30 for moving said plate to line-space the work-sheet irrespective of the position of the aligning plate as adjusted for one of said business periods.

35. In a front-strike typewriting machine, the combination with a platen, of an aligning plate erected at the front of the platen above the printing line and provided with a leading-edge gage, means for adjusting said aligning plate and leading-edge gage relatively to the printing line to occupy different 40 positions corresponding respectively to different successive business periods, and means for setting said plate and gage to different mechanically-determined line-space 45 positions irrespective of the business period positions thereof.

50. In a front-strike typewriting machine, the combination with a platen, of an aligning plate erected at the front of the platen above the printing line, means for adjusting said plate relatively to the printing line to occupy different positions corresponding respectively to different successive business periods, means for detaining a work-sheet 55 on said plate, and a line-spacing device for moving said plate to line-space the work-sheet held thereon irrespective of the adjustment of said plate for any one of said business periods.

60. In a front-strike typewriting machine, the combination with a platen, of an aligning plate erected at the front of the platen above the printing line, a pair of 65 mounts upon which said plate is movable for line-spacing, a line-spacing device for

moving said plate on said mounts to line-space a work-sheet held upon the plate, a pair of upright bars upon which said mounts are shiftable, means for locating and detaining said mounts at mechanically-determined 70 master line-space stages or intervals relatively to the printing line to occupy a series of different master line-space positions corresponding to the respective minor business periods comprised in a major business 75 period, for thereby correspondingly setting said plate independently of said line-spacing movement thereof, means to detain the work-sheet on said plate to move therewith, and means for line-spacing said plate relatively to said mounts. 80

20. In front-strike typewriting machine, the combination with a platen, of an aligning plate erected at the front of the platen above the printing line, a mount on which 85 said plate is movable to vary its distance from the printing line, a line-space device for moving said plate on said mount to line-space a work-sheet held upon the plate, means for holding the work-sheet on said 90 plate, and adjusting means for locating and detaining the plate-carrying mount in different positions corresponding respectively to different successive business periods. 95

21. In a front-strike typewriting machine, the combination with a platen, of a leading-edge gage at the front of the platen above the printing line, means for locating and detaining said gage at mechanically-determined master line-space stages or intervals 100 relatively to the printing line to occupy a series of different master line-space positions corresponding respectively to different successive business periods, a line-spacing device for line-spacing said gage independently of said locating and detaining means to line-space a work-sheet held against said gage, and means for detaining the work-sheet against said gage, irrespective of the 105 positions of the latter, to effect line-spacing of the work-sheet by the line-spacing movement of said gage. 110

22. In a front-strike typewriting machine, the combination with a platen, of an aligning plate erected at the front of the platen above the printing line and provided with a leading-edge gage, a mount upon which 115 said aligning plate is movable for line-spacing, a line-spacing device for moving said plate on said mount to line-space a work-sheet held on said plate and against said gage, a support upon which said mount is shiftable, means for locating and detaining said mount on said support at mechanically-determined master line-space stages or intervals relatively to the printing line to occupy a series of different master-line-space positions corresponding to successive business periods, 120 and means for detaining the work-sheet on 125 said support. 130

said plate and against said gage irrespective of the positions of the latter to effect line-spacing of the work-sheet by the line-space movement of said plate.

23. In a front-strike typewriting machine, the combination with a platen, of an aligning plate erected at the front of the platen above the printing line, a pair of mounts upon which said plate is movable for line-spacing, a line-spacing device for moving said plates on said mounts to line-space a work-sheet held upon the plate, a pair of upright bars upon which said mounts are shiftable, means for locating and detaining said mounts at mechanically-determined master line-space stages or intervals relatively to the printing line to occupy a series of different master line-space positions corresponding to the respective minor business periods comprised in a major business period for thereby correspondingly setting said plate independently of said line-spacing movement thereof, and means for holding the work-sheet on said plate to effect line-spacing of the work-sheet when said plate is line-spaced.
24. In a typewriting machine, a cylind-

rical platen, a carriage therefor, a carriage-return finger-piece on the carriage, a gage-plate at the delivery side of the platen, and 30 gage-plate-line-spacing means including a finger-piece operable to the left and so located on the carriage that it and the carriage-return finger-piece may be engaged at the same time by one hand of the operator and 35 operated concomitantly.

25. In a typewriting machine, a cylindrical platen, a gage-plate at the delivery side of the platen, and gage-plate-line-spacing means including a reciprocable finger-piece 40 operable in one direction to advance the gage-plate through successive line-space intervals and in the opposite direction to return the gage-plate through such line-space intervals.

26. In a typewriting machine, a platen, work-sheet-gripping means, a finger-piece, and a finger-piece-actuated pin-and-cam-slot connection to act on said gripping means to line-space a work-sheet gripped thereby.
